UNITED STATES PATENT OFFICE.

HENRY ONESIME STAUFFER, OF PONTS MARTEL, SWITZERLAND.

DESIGN FOR A WATCH-MOVEMENT.

SPECIFICATION forming part of Design No. 12,926, dated May 9, 1882.

Application filed March 27, 1882. Term of patent 7 years.

To all whom it may concern:

Be it known that I, HENRY ONESIME STAUFFER, of Ponts Martel, in the Republic of Switzerland, have originated and produced a new 5 and Improved Design for Watch-Movements, of which the following is a description.

My improved design consists in a circular watch-plate having the several bridges and the cock made in the form of the numerals 10 "1776," of the configuration represented in the accompanying drawing, and so arranged on the said plate that all portions of them are within the circular outline or periphery of the said plate.

15 A designates the watch-plate, which is of circular shape.

B designates the cock, and C, D, and E designate respectively the several bridges. The bearing *a* for the central arbor or spindle 20 of the watch is in the bridge D, and the other bridges, C and E, contain bearings *b* for the other arbors or spindles of the movement. As clearly seen, the cock B is made in the form of the numeral "1," the bridges C and D are 25 made in the form of the numeral "7," and the bridge E is made in the form of the numeral

"6." The cock and the three bridges therefore form the numerals "1776." Through the cock and bridges are inserted screws *c*, and certain of the screws pass through lugs or ears 30 *d*, which are so formed as to add to the ornamental appearance of the design. The body portions of the bridges C and D are both curved correspondingly to the inner edge of the bridge E, and all the bridges are of such outline as 35 to present a highly-ornamental appearance. As clearly shown, the cock B and the bridges C, D, and E are so disposed on the plate A that they are entirely within the circular outline or periphery thereof.

40 What I claim, and desire to secure by Letters Patent, is—

The design consisting of the watch-plate A, of circular form, and the cock and bridges made in the form of the numerals "1776," of 45 the configuration herein represented, and arranged within the circumference of said plate, as herein described.

H. ONESIME STAUFFER.
